UNITED STATES PATENT OFFICE

150,214

DESIGN FOR A TRANSFORMER

Wilbur K. Dickinson, Lynn, Mass., assignor to
General Electric Company, a corporation of
New York

Application August 9, 1946, Serial No. 132,381

Term of patent 14 years

(Cl. D26—13)

To all whom it may concern:

Be it known that I, Wilbur K. Dickinson, a citizen of the United States, residing in Lynn, in the county of Essex, State of Massachusetts, have invented a new, original, and ornamental Design for Transformers, of which the following is a specification, reference being had to the accompanying drawing, forming a part thereof.

In the drawing, Fig. 1 is a side elevational view of a transformer showing my new design; Fig. 2 is a plan view of the same transformer; Fig. 3 is an end elevational view of the transformer, and Fig. 4 is a perspective view of the transformer.

I claim:

The ornamental design for a transformer, substantially as shown.

WILBUR K. DICKINSON.
